(57) **CLAIM**

The ornamental design for a printer, as shown.

DESCRIPTION

FIG. 1 is a front and right side perspective of a printer showing our new design;

FIG. 2 is a rear and left side perspective thereof;

FIG. 3 is a front elevation thereof;

FIG. 4 is a rear elevation thereof;

FIG. 5 is a left elevation thereof;

FIG. 6 is a right elevation thereof;

FIG. 7 is a plan view thereof;

FIG. 8 is a bottom view thereof; and,

FIG. 9 is a front and left side perspective view thereof, showing the collection tray in the extended position.

The broken lines are for illustration only and form no part of the claimed design.
